(57) **CLAIM**

The ornamental design for a silicone food mold, as shown and described.

DESCRIPTION

FIG. 1 is a top, right side and front perspective view of a silicone food mold, showing my new design with the top, left side and rear perspective view being identical,

FIG. 2 is a top view thereof;

FIG. 3 is a right side view thereof, with the left side views being identical;

FIG. 4 is a front view thereof, with the rear views being identical; and,

FIG. 5 is a bottom view thereof.

1 Claim, 2 Drawing Sheets(56)
